OR D 18,741

Design No. 18,741, dated November 20, 1888.

UNITED STATES PATENT OFFICE.

HENRY G. DAWSON AND WILLIAM R. DAWSON, OF CHICAGO, ILLINOIS.

DESIGN FOR A MANTEL.

SPECIFICATION forming part of Design No. 18,741, dated November 20, 1888.

Application filed October 23, 1888. Serial No. 288,954. Term of patent 7 years.

To all whom it may concern:

Be it known that we, HENRY G. DAWSON and WILLIAM R. DAWSON, of Chicago, in the State of Illinois, have invented and produced a new and original Design for a Fire-Place Mantel, of which the following is a specification, reference being had to the accompanying photographic illustration, forming part thereof.

The figure is a front perspective view of a fire-place mantel showing our design.

The leading feature of our design consists in the ornamentation of the frame, which is made up of a number of quadrilateral figures distinguished from each other by varied surface configuration, the figures being arranged on the frame as shown relatively to one another.

A designates the side pieces of the frame; B, an inner frame; C, a panel or piece over the fire-place; D, brackets under the mantel-shelf, and E wings attached at the top to the side of the side pieces of the frame.

The side pieces, A, are ornamented with quadrilateral figures a a' , the surface of the former being plain and that of the latter being marked with a series of fine lines drawn over the same close together.

The surface of the inner frame is ornamented with carved work b , in relief on a roughened background, and the upright parts of said frame thus ornamented form a border along the inner margin of the side pieces, A.

The surface of the panel over the fire-place has three quadrilateral figures, two of which,

c c , at the ends of the panel, comprise a network of interlaced ropes and the other or central one, c' , an arabesque group. The margins above and below this panel are distinguished by filigree of varied patterns worked in or on the surface along the whole length of the panel.

At the ends of the panel and the margins thereof the brackets stand out under the mantel-shelf and are each provided with a head, d . Below the brackets is a square figure, b' , which occupies each upper corner of the inner frame, B. This figure has a rosette in the center.

The wings E are made in imitation of a shell.

What we claim, and desire to secure by Letters Patent, is—

The design for a fire-place mantel herein shown and described, consisting of the alternate quadrilateral figures a a' along the side pieces, bordered with the carved work b along their inner margins, and the figures c c and c' over the fire-place, consisting of interlaced rope-work and an arabesque group worked in or on the surface of the panel and bordered with a strip of filigree above and below, as described and shown.

HENRY G. DAWSON.

WILLIAM R. DAWSON.
